UNITED STATES PATENT OFFICE.

SAMUEL STEINFIELD AND WILLIAM R. FOUST, OF LEETONIA, OHIO.

SHOW-CASE.

SPECIFICATION forming part of Letters Patent No. 364,448, dated June 7, 1887.

Application filed November 23, 1886. Serial No. 219,686. (No model.)

To all whom it may concern:

Be it known that we, SAMUEL STEINFIELD and WILLIAM R. FOUST, both of Leetonia, in the county of Columbiana and State of Ohio, 5 have invented a new and Improved Show-Case, of which the following is a specification, reference being had to the annexed drawings, forming a part thereof, in which--

Figure 1 is a front elevation of our improved show-case, and Fig. 2 is a vertical transverse section taken on line $x-x$ in Fig. 1.

Similar letters of reference indicate corresponding parts in both views.

The object of our invention is to provide a 15 show-case for displaying and storing shirts, collars, and similar articles.

Our invention consists in a show-case having inclined sides and a series of compartments for containing shirts, collars, &c., the 20 show-case being provided with a sliding sash containing the glass, and having a sliding shelf for the convenience of the salesman in handling the goods.

It also further consists in notched bars 25 placed in the upper and lower part of the show-case and a board adapted to be placed in the notches of the bars for holding the shirts up to the front of the show-case.

To the table-top A are secured the back 30 pieces, B B', of the show-case, the said back pieces being inclined toward each other and meeting at a point above the center of the table. Outside of the back pieces, B B', are secured frames C C', parallel with the back 35 pieces and provided with the sash D, containing glass E. The two show-cases F F' thus formed are oppositely arranged with respect to each other, and the sashes D are capable of sliding upward through the tops of the frames 40 C C'. The spaces between the frames C C' and the backs of the cases are closed by hinged lids G, and the spaces between the backs B B' of the ends of the show-case are filled by a triangular board, H. The ends of 45 the show-case are closed by panels.

A molding, I, surrounds the upper portion of the case, and a molding, J, surrounds the lower portion thereof and forms a finish between the show-case and the table-top A.

Underneath the table-top A are arranged 50 drawers K K', which may be drawn out from opposite sides of the table, and between the

drawers and the table top are arranged sliding shelves L L'.

The upper ends of the sash D are provided 55 with a flexible strip, M, of cloth or other suitable material, for closing the spaces between the sash and the frames C C' and excluding dust. A portion or all of the compartments of the show-case are provided with shelves 60 N, near the top, for receiving collars, cuffs, and other small articles. At the bottom and top of each show-case are placed notched bars O, for holding the board o', for supporting the shirts and other articles contained by the show-case near the front of the case, and preventing them from slipping.

Our improved show-case may be made of wood, metal, celluloid, or other suitable material, and it may have any number of compartments, a sash, D, and glass E being provided for each compartment. Each sash is provided with a bowed spring, D', attached to the edge thereof and bearing against the frame C for automatically holding the sash at any 75 desired height.

It is obvious that a case may be constructed according to our improvement with only one inclined show-case instead of two, a case so made being adapted to be placed against a 80 wall.

Having thus fully described our invention, we claim as new and desire to secure by Letters Patent—

1. In a show-case, the combination of the 85 inclined backs B B', the inclined frames C C', the sashes D, adapted to the frames C C', the strip M, attached to the upper ends of the sashes, and the inclosing-pieces of the ends and top of the case, substantially as described. 90

2. The combination, with the inclined show-cases F F', of upper and lower horizontal notched bars O and inclined boards o', substantially as and for the purpose specified.

3. The table provided with a top, A, the 95 sliding shelves L L', and drawers K K', the inclined show-cases F F', formed of the backs B B', frames C C', and the sash D, provided with the glass E, substantially as described.

SAMUEL STEINFIELD.
WILLIAM R. FOUST.
